REGULATING ELECTRIC PRECIPITATORS

Bengt Berg, Bandhagen, Sweden, assignor to A.B. Svenska Fläktfabriken, Stockholm, Sweden

Filed June 27, 1958, Ser. No. 745,212

Claims priority, application Sweden July 3, 1957

1 Claim. (Cl. 183—7)

The present invention relates to a system for governing regulating means for electrical precipitators and consists of electrical control elements placed in the primary circuit of a high tension transformer. The control elements produce impulses, either directly or through an amplifier, resulting in the regulation of the voltage or current and control of the cleaning unit in the filter etc., in the event of flash-overs in the filter.

The efficiency with which particles are filtered in an electrostatic precipitator is determined by a large number of factors, *inter alia*, current and voltage. The amount of voltage required to produce corona current sufficient to cause a good particle charge is determined by the geometric configuration of the electrodes, the composition of the gas, its temperature and pressure, and the nature of the particles. In the case of certain simple gases and gas compositions the voltage and current can be estimated theoretically if the filter is completely clean. Similarly, under such conditions, the flash-over voltage can be calculated. It is, however, quite obvious that these conditions can never be satisfied in practice and the only solution is to use values based on experience.

As regards the flash-over voltage, it is found that the actual value is considerably below that calculated theoretically for a clean filter. Causes of the flash-over occurring at lower voltages may be changes in the distance between the electrodes, *e.g.*, in that some of the very large number of emission wires accidentally swing as a result of heat stresses caused by rapid variations in temperature or the particle load. The particles may, owing to their electrical properties, cause the corona discharge to vary rapidly and unevenly, thus giving rise to an increased tendency towards isolated flashovers in the precipitator. The fall of particles caused when the filter is shaken for cleaning purposes may also cause flash-overs etc. It is evident from the foregoing that flash-overs may occur in the precipitator at any voltage, even though the tendency to flash-overs is, of course, increased at higher voltages. It is therefore preferred to define the flash-over limit as that voltage at which the flash-over frequency starts rapidly to increase. This limit is raised or lowered depending on the variations in filter operation. From the point of view of precipitation, the best results are obtained if the filter voltage can be kept in the region of the flash-over limits as thus defined.

A primary object of the present invention, therefore, is to provide regulating means for an electric precipitator which automatically maintains the voltage applied to the precipitator at the highest possible value without causing excessive flashovers.

More specifically the present invention provides in the primary circuit of a precipitator, a transducer which serves the triple function of quenching flashovers, providing an impulse to a regulating circuit upon occurrence of flashovers, and regulating the voltage applied to the precipitator to maintain the highest possible voltage without excessive flashovers.

With the foregoing in mind, the invention is more fully

set forth hereinafter with the reference to the accompanying drawing wherein:

Fig. 1 is a graphical representation of the current-voltage characteristics of an electrostatic precipitator under 5 different operating conditions;

Fig. 2 is a schematic diagram of a control system for an electrostatic precipitator made in accordance with the present invention; and

Fig. 3 is a graphical representation of typical operation 10 of the precipitator of the present invention showing the variation in voltage applied to the precipitator over a period of time when the precipitator is controlled in accordance with the present invention.

The current and voltage characteristics of an electrostatic precipitator under varying operational conditions are, in principle, as shown in Fig. 1. Curve *a* is the mean curve considered as applicable to the filter. Curves *b*, *c* and *d* indicate variations in operational conditions. I_m indicates the current which, from the point of view of 15 particle charging, is calculated as desirable for the filter. The filter or precipitator-electrodes have been so dimensioned that when the current I_m is passed through the precipitator, the voltage U_m normally obtained is at a value, which lies at a suitable "safety-factor distance" 20 from the flash-over limit. To illustrate the matter further, let us consider the following conditions. Suppose that the flash-over limit and the mean points of the filter characteristics are as shown by U_o and *a* respectively. This results in the desirable condition whereby U_m is very near 25 the flash-over limit. If the operational conditions are now altered so that curve *b* is applicable, while U_o remains unchanged, the filter voltage will exceed U_o if the current I_m is maintained. It will then be necessary to reduce the current to the value I' . True, the filter voltage will still 30 be in the region of U_o , but the filter current will be too low to charge the particles effectively. If, instead, the filter characteristic is altered to position *c*, the voltage will be lower than U_o if I_m is maintained. In order to restore the voltage to the region of U_o the filter current must be 35 greatly increased to the value I'' , and this often means an impossible overloading of the rectifier if this latter unit is economically designed for normal operation.

It will be seen from the foregoing that it is impossible 40 always—or even often—to keep the filter voltage near the flash-over limit. For the best possible function under all conditions, the filter should be so calculated that the lowest value for the flash-over limit is in the region of the highest value for the filter voltage (at current I_m , curve *b*). The electrostatic precipitator is fed from a rectifier which, for reasons of economy, ought not to be 45 designed for currents notably higher than I_m .

It has been mentioned earlier that, under normal circumstances, it should not be reckoned that the filter voltage can always be kept in the region of the flash-over limit. However, it is possible under certain circumstances 50 and, in such cases, the rectifier must be regulated. If the operational conditions are subject to rapid and frequent change, the supervisory staff must make constant adjustments to the rectifier. As a rule, the current will be reduced and maintained at such a low level that the 55 supervisory staff will not be troubled by a high frequency of flash-overs. As a result, the capacity of the precipitator will not be fully utilized. In this case, it is easy to augment the rectifier with an automatic regulator.

60 The present invention refers to an improved form of such automatic control, characterized in that the impulse generator for the automatic unit consists of a transducer designed to function simultaneously as a voltage regulator, an impulse generator, and as a device for markedly quenching the flashovers. The transducer of 65 the present system is a direct-current magnetized alter-

nating-current choke coil, and thus includes such devices as saturable reactors and magnetic amplifiers. The amplification of the emitted impulses is achieved by the use of a suitably designed amplifier consisting of a thyratron relay. One form of the device especially intended for regulation of the current or voltage to the maximum value as regards flash-over includes an amplifier unit consisting of a thyratron relay, combined with a time relay, both controlling a stage regulator in such a way that the current or voltage are stepped-up at regular intervals, while in the case of flash-over, the current or the voltage are stepped-down in stages. The device according to the invention can also be used for starting the cleaner in the precipitator when the current in the precipitator has been stepped-down below a predetermined minimum value, this device being characterized in that the stage regulator is fitted with a limit switch for connecting or energizing the cleaner.

In the illustrated embodiment of the control system, the main line connection 1 has a main switch 2 for the entire installation. A control relay 3 can be switched on and off by means of the manually operated contacts 3a and 3b. A transducer 4 of special design is coupled into the primary circuit of the electrostatic precipitator 7. The electrostatic precipitator is provided with a high tension transformer 5, and a high tension rectifier 6. A rectifier 8 for the direct-current pre-magnetization of the control windings of the transducer is connected to an intermediate transformer 9 for this rectifier. A regulating transformer 10 at one side is connected to the supply line 17 for the operating current to the automatic device and at the other side to the primary circuit of the transformer 9. The transformer 10 is fitted with a reversible regulating motor 11, which is caused to rotate in different directions by the alternative connection of the relays 12 and 13. This switch-over can either be effected manually by contacts 12a and 13a or automatically by switch contacts 12b and 13b. The switch 12b is operated by a time relay 15, while switch 13b is operated by a thyratron relay 14 consisting of a thyratron 14a, a capacitive time regulation circuit 14b and a rectifier 14c. The latter rectifier is connected to transducer 4 by an intermediate transformer 16. A time relay 18 with an exceedingly delayed action (about 30 seconds) is connected in the operating circuit to the main control relay 3, this time relay breaking the supply of current to the electrostatic precipitator 7 in the event of a state of short circuit in the precipitator. A limit switch 20 responsive to the regulating arm of the transformer 10 is actuated by the regulating motor 11 when the current in the filter 7 is stepped down below a predetermined minimum. The limit switch, when closed, switches in the cleaning devices built in to the precipitator. These cleaning devices (not shown in detail on the drawing) are connected to the automatic control system at the points marked 19.

The control system according to the invention functions in the following manner: Assuming the motor-operating regulating transformer 10 is applying a low voltage to the precipitator 7, the voltage may be increased without danger of excessive flashovers. To this end, the timer 15 operates at regular intervals to close the switch contacts 12b for a timed period. Upon closure of the contacts 12b, the relay 13 is energized which both maintains the relay 12 de-energized and energizes the motor 11 of the transformer 10 to cause rotation of the motor in a direction to step-up the voltage applied to the precipitator 7. The timed period causes the voltage to rise a predetermined amount during each closure of the contacts 12b. The voltage increases periodically the predetermined amount until excessive flashovers occur in the precipitator 7. When a flash-over takes place in the precipitator, the transducer 4 momentarily accepts the entire line voltage. According to the invention the trans-

ducer 4 is designed to have a marked flash-over quenching function, so that the transducer in this case serves both as a regulator for the rectifier and as a flash-over sensor. The rise in voltage in the transducer 4 generates an impulse which is transmitted through the intermediate transformer 16, the capacitive time regulation circuit 14b, and the rectifier 14c to the thyratron 14a which, whenever the frequency of flashovers is sufficient to accumulate enough energy in the circuit 14b to operate the thyratron 14a, closes the switch 13b, energizing the relay 12 which both maintains the relay 13 de-energized and energizes the motor 11 to cause rotation thereof in the direction to step-down the voltage applied to the precipitator 7. In this way, the current to the electrostatic precipitator 7 is reduced, as is also the voltage. The length of time the thyratron relay remains closed to cause such rotation of the motor, and thereby the magnitude of the drop in voltage for every flash-over, can be regulated by means of the variable resistances in the capacitive time-regulation circuit 14b. As soon as the intended step-down has ceased, the regulating motor 11 is reversed by an impulse from the timer 15, which energizes the relay 13. As a result, the voltage is stepped-up again periodically and this regulation continues until a new step-down process is introduced. A typical sequence of operation is illustrated in Fig. 3. In this way it is possible to maintain the filter voltage in the region of the above-mentioned flash-over limit, i.e., the voltage above which the flash-over frequency rapidly starts to rise. Should a state of short-circuit arise in the filter, the supply of current to the electrostatic precipitator 7 is disconnected via the time relay 18, which is so designed as to function with an exceedingly delayed action. When the flashovers become so frequent that the voltage is stepped-down to the point where the arm of the regulating transformer 10 closes the limit switch 20, the cleaning devices of the precipitator are energized through the connections 19.

What I claim is:

For an electrical precipitator having a high voltage transformer, a unit connected in the primary circuit of said transformer incorporating a transducer having control windings to regulate the voltage applied to said precipitator, said transducer having an especially high-current-limiting effect inducing a counteracting voltage within said transducer upon flashover in said precipitator to quench the same, a control circuit including a motor-operated regulating transformer connected to the control windings of said transducer and operable selectively to raise and lower the voltage applied to said precipitator, a timing device connected to said control circuit to operate at regular intervals the transformer in one direction for a timed period and thereby periodically raise said applied voltage a predetermined amount, and a sensing circuit responsive to said flashover-induced voltage in said transducer including a capacitive time-regulation circuit operable upon occurrence of repeated flashovers and resulting accumulation of energy in said capacitive circuit to disconnect said timing device from said control circuit and to operate the transformer in the opposite direction for a timed interval and thereby lower the applied voltage a predetermined amount, whereby said transducer serves as both a flashover sensor and a regulator to apply the highest possible voltage to the precipitator at all times without excessive flashovers.
